UNITED STATES PATENT OFFICE.

SELLMAR M. JACOBY, OF NEW YORK, N. Y.

DESIGN FOR A PRESSER-BAR.

SPECIFICATION forming part of Design No. 25,882, dated August 4, 1896.

Application filed March 6, 1896. Serial No. 582,145. Term of patent 14 years.

To all whom it may concern:

Be it known that I, SELLMAR M. JACOBY, of the city and county of New York, in the State of New York, have invented and produced a new and original Design for a Presser-Bar for Fur-Sewing Machines, of which the following is a specification, reference being had to the accompanying drawings, forming a part thereof.

The essential features of my design consist in a presser-bar for fur-sewing machines presenting a **U** shape when viewed in side elevation and a **U** shape when viewed in top plan, one of the branches of the **U**-shaped bar being extended at its free end in three different directions substantially at right angles to one another.

The portions of the bar which form the

branches of the **U** are denoted by A and C. The portion of the bar which forms the bight 20 of the **U** is denoted by B, and the extensions at the free end of one of the branches at substantially right angles to one another are denoted by B', B², and C.

In the accompanying drawings, Figure 1 is 25 a view of the presser-bar in perspective. Fig. 2 is a view in side elevation. Fig. 3 is a view in front elevation, and Fig. 4 is a plan view.

What I claim is—

The design for a presser-bar for fur-sewing 30 machines, substantially as shown and described.

SELLMAR M. JACOBY.
